UNITED STATES PATENT OFFICE.

ERNEST SIMPSON FISHER, OF PORTLAND, OREGON.

TROUSERS-STRETCHING DEVICE.

1,157,521.

Specification of Letters Patent. Patented Oct. 19, 1915.

Application filed June 6, 1914. Serial No. 843,472.

To all whom it may concern:

Be it known that I, ERNEST S. FISHER, a citizen of England, residing at Portland, in the county of Multnomah and State of Oregon, have invented new and useful Improvements in Trouser-Stretching Devices, of which the following is a specification.

This invention relates to improvements in trousers stretching devices and has particular application to devices of that class adapted to be inserted in the legs of the trousers.

In carrying out the present invention, it is my purpose to improve and simplify the general construction of trousers stretching devices of the class described and to provide a device wherein the component parts may be contracted or drawn together and held in such position while the device is being inserted in the legs of the trousers and wherein such parts may be released succeeding the insertion of the device whereby the device will expand thereby stretching and creasing the trousers' legs.

A further object of my invention is to provide a device of the type set forth which will embrace the desired features of simplicity, efficiency and durability, which may be manufactured and marketed at a minimum expense and which may be applied to the trousers and removed therefrom quickly and conveniently.

With the above and other objects in view, the invention consists in the construction, combination and arrangement of parts hereinafter set forth in and falling within the scope of the claim.

In the accompanying drawing: Figure 1 is a view in side elevation of a trousers creasing device constructed in accordance with the present invention. Fig. 2 is a vertical sectional view on the line 2-2 of Fig. 1. Fig. 3 is a fragmentary perspective view of the expanding devices.

Referring now to the drawing in detail, 1 and 2 designate strips of wood or other suitable material placed edge to edge and having the outer edges thereof tapered to provide relatively thin edges. Suitably fastened to the inner edge of each strip adjacent to the opposite ends thereof are plates 3 formed with apertures alining with openings in the adjacent edge of the strip to provide sockets 4, the sockets of one strip alining with those in the other strip. Seated within the sockets 4 in the strip 1 and suitably secured therein are metal rods 5 projecting outwardly of the inner edge of the strip and toward the inner edge of the strip 2. Seated within the sockets 4 in the inner edge of the strip 2 and suitably secured therein are metal rods 6 projecting outwardly of the inner edge of the strip 2 and toward the inner edge of the strip 1. The rods 5, 5 carried by the strip 1 overlap the rods 6, 6 respectively carried by the strip 2 and encircling each pair of overlapping rods 5, 6 is a coiled contractile spring 7 having one end thereof passed through and secured to an eye 8 formed on the outer end of the rod 6 and the opposite extremity passed through and secured to an eye 9 formed on the outer extremity of the adjacent rod 5. These springs 7, 7 act, normally, to slide the rods 5 and 6 one upon the other to move the strips 1 and 2 away from each other thereby expanding the creasing device. In order to hold the strips against outward movement under the action of the springs, suitable means is employed.

In the present instance, a hook 10 is carried by the eye 8 on the rod 6 at one end of the strip 2 and is adapted to engage a lug 11 formed on the plate 3 carried by the adjacent portion of the strip 1. The plate 3 at the opposite end of the strip 1 is formed with a lug 12 and connected to the lug 12 is a hook 13 adapted to enter an eye formed in a lug 14 carried by the plate 3 on the adjacent end of the strip 2.

The rods 5 and 6 at one end of the device are relatively long as compared with those at the opposite end of the device so that the strip 1 will be held at an angle to the strip 2 thereby giving the device a tapering outline. In practice, the hook 13 is engaged with the eye in the lug 14 and the hook 10 engaged with the lug 11 thereby holding the device contracted. The device is now inserted in one leg of the trousers and the hooks 10 and 13 released whereby the springs 7, 7 react and so slide the rods 5 and 6 one upon the other with the effect to move the strips 1 and 2 outwardly of each other. In placing the device in the trousers the strip 1 is disposed adjacent to the back crease while the strip 2 is disposed adjacent to the front crease and when these strips are expanded or moved away from each other under the action of the springs the edges of the strips 1 and 2 enter the respective creases thereby stretching the trousers.

leg and holding the crease therein. The strip 1 at one end thereof is preferably of greater width than the remaining portion so as to fit the hip portion of the trousers' leg.

5 In the present instance, the end of each rod 5, 6 within the particular socket is bent upon itself as at 15 and thence extended at right angles as at 16, the bent portion 15 of the rod coacting with the adjacent part 10 thereof to frictionally engage the wall of the socket thereby holding the rod securely to the strip.

15 It will be understood that when stretching and creasing the trousers one device is disposed in each leg.

20 While I have herein shown and described one preferred form of my invention by way of illustration, I wish it to be understood that I do not limit or confine myself to the 25 precise details of construction herein described and delineated, as modification and variation may be made within the scope of the claim without departing from the spirit of the invention.

25 I claim:

A trousers stretching device comprising

Copies of this patent may be obtained for five cents each, by addressing the "Commissioner of Patents. Washington, D. C."

strips, aligned sockets on the inner edge of said strips adjacent their ends, plates secured to the inner edges of the strips and having apertures therein adapted to register with said sockets, one end of the said plates being bent at right angles, the said bent portion being provided with an eye, rods carried by the inner edge of each strip and projecting toward the similar edge of the adjacent strip and overlapping each other, coiled contractile springs surrounding the overlapping ends of the rods and having the opposite extremities thereof secured to the outer ends of said rods, the outer end of one rod terminating in a loop, and a hook attached to said loop, the free end thereof adapted to engage the eye in one of said plates thereby holding said strips against outward movement under the action 45 of said spring.

In testimony whereof I affix my signature in presence of two witnesses.

ERNEST SIMPSON FISHER.
